CLAIM

The ornamental design for a double server tray as shown, and described.

DESCRIPTION

FIG. 1 is a top plan view of a double server tray, showing my new design;

FIG. 2 is a bottom plan view thereof;

FIG. 3 is a front side elevational view of the double server tray shown in FIG. 1, the rear side elevational view being substantially identical;

FIG. 4 is a left side elevational view thereof, the right side elevational view being substantially identical; and FIG. 5 is a sectional view as taken along line 5—5 in FIG. 1.

FIG. 4

FIG. 5
